UNITED STATES PATENT OFFICE.

FREDERICK JOHN CORBETT, OF SOUTH YARRA, VICTORIA, AUSTRALIA.

APPARATUS FOR MANUFACTURING WHITE LEAD.

SPECIFICATION forming part of Letters Patent No. 694,139, dated February 25, 1902.

Application filed May 24, 1901. Serial No. 61,676. (No model.)

To all whom it may concern:

Be it known that I, FREDERICK JOHN CORBETT, a subject of the King of Great Britain and Ireland, residing at 11 Portland Place, 5 South Yarra, county of Bourke, State of Victoria, Commonwealth of Australia, have invented certain new and useful Improvements in Apparatus for Manufacturing White Lead, of which the following is a specification.

10 The object of this invention is to provide an apparatus in which the manufacture of white lead can be effectively and economically carried on; and the invention consists in the combination, in an apparatus for making 15 white lead, of a settling-chamber, a float in said settling-chamber, a siphon-pipe connected with said float and extending outside the chamber, and a discharge-pipe communicating with the lower part of the chamber; and 20 the invention consists, further, in the combination, in an apparatus for making white lead, of a plurality of settling-chambers, a 25 vacuum-pan, discharge-pipes, each connecting one of said settling-chambers with the vacuum-pan, a spout connected with said 30 vacuum-pan, a float in each settling-chamber, valved siphon-pipes, one to each float, connecting the same with the spout, a condenser connected with said spout, and an air-pump connected with said condenser.

In the accompanying drawings, Figure 1 is a front view, with parts broken away, of my improved apparatus for making white lead. Fig. 2 is a side view of the apparatus, also 35 with parts broken away. Fig. 3 is a vertical section through one of the floats of the apparatus, and Fig. 4 is a detail side view of the plug for closing the carbonating-chamber of the apparatus.

40 Similar letters of reference indicate corresponding parts.

Referring to the drawings, A indicates an upper reservoir, which communicates by a pipe a, having a valve a', with a carbonating-chamber C, provided with an agitator c, journaled therein and of any suitable form for 45 agitating the contents of the chamber. The chamber C is surrounded by a jacket C', to which steam for heating is supplied through 50 a suitable pipe c³, provided with a valve c'.

B is a hopper provided with a discharge-tube b, preferably flexible and which termi-

nates in a tapering nozzle b², adapted to enter an opening in the upper part of the chamber C, which opening is closed, when the carbonation operation is in progress, by means of a suitable screw-plug b¹ or any other suitable device. The hopper B is supported in any suitable manner, preferably, however, by means of a bail b³, to which is attached a 55 spring-balance b⁴, which is suspended by means of a hook b⁵ to any suitable point of support. From the lower part of the carbonating-chamber C extends a pipe c', having a valve c² and communicating with the interior 60 of a settling vat or chamber D. The upper part of the carbonating-chamber C is connected by a valved pipe n with the upper part of the vat D. Two of these vats, with their connecting-pipes c' n, are arranged as shown 65 in Fig. 1. Each vat consists of an outer shell d⁶, an inner perforated shell d⁷, and a lining d⁸ of canvas or other suitable close-meshed filtering material within said inner shell. The pipe c' is connected with the interior space of 70 the vat D—i. e., the space within the filtering medium d⁸. Within each vat is arranged a float d, counterbalanced by a weight d', which is connected with the float by a wire d², passing through the top of the vat D and 75 over a pulley d³, mounted rotatably upon an arm r of a standard r', rising from the floor R or from any other point of support. To the float is connected a flexible siphon-pipe 80 e of rubber or other suitable material. The 85 float d is made of wood or other suitable material of sufficient lightness as to float upon the surface of the liquid employed and is provided with a bore d⁴, extending through the same. The coupling d⁵ connects the pipe 90 e with said bore, said pipe being by the bore placed in communication with the portion of the vat below the float. The upper end of the flexible tube e is connected with a valved pipe e', which passes through the wall of the 95 vat at the upper part of the same and thence in downward direction, its lower end being connected with the spout g of a suitable vacuum-pan G. The interior space of each vat D is connected at its lower portion by a 100 suitable valved pipe g' with said vacuum-pan G, and the latter is provided at its interior with an agitator G' of any suitable construction, the shaft g² of said agitator being jour-

naled at its lower end in a cross-bar g^4 of the pan and at its upper end in a cap g^5 of the spout g of the pan and provided outside of the same with a bevel-gear g^3 or other means for operating the same, as shown in Fig. 1. The lower end of the pipe e' is located below the level of the float, and the pipes e e' form thereby a siphon-pipe. The space between the exterior and interior shells d^6 d^7 of the settling-vat or filtering-vat D communicates by a pipe e^3 with the spout g . The lower end of the vacuum-pan is connected by a pipe i , having a valve i' , with pipes i^2 , delivering into settling vessels I. The pan is preferably provided with observation-windows m . To the outer end of the spout g of the vacuum-pan is connected a condensing-coil F, which is surrounded by a suitable liquid vessel f , provided with an overflow f^4 , the whole forming a condenser for the vapors distilled off from the material in the pan. The lower end of the coil F passes through the vessel f and delivers into a lower liquid-reservoir A'. This is a closed vessel, and from the upper portion of the same rises and then descends a pipe o into a vessel O, filled with glycerin or other suitable material, thus forming a seal permitting the escape of air or gas from the vessel A', but not permitting ingress of the same through the pipe o . To the coil F below its tank is connected by a pipe f' an air-pump E', which pump also communicates by pipe f^2 with the tank A'. From the upper portion of said tank A' a pipe a^3 runs directly to the upper liquid-reservoir A and from the lower portion of said tank A' a pipe a^2 communicates with the pump E and another pipe a^5 connects said pump with the upper reservoir A.

40 A solution of from thirty to ninety per cent. of acetal aldehyde (C_2H_4O) and from seventy to ten per cent. of commercial acetic acid of thirty-five per cent. strength or other suitable solvent liquid is placed in the upper reservoir A. A quantity of this solution is allowed to flow through pipe a , so as to fill the carbonating-chamber somewhat less than half-full. A suitable weight of litharge (indicated by the spring-balance b^4) is placed in 45 the hopper B, the same being retained in the hopper during the weighing by means of a suitable slide or valve b^6 at the lower part of the hopper. The valve is drawn and the litharge in quantity sufficient to fill the chamber C approximately half-full allowed to flow into the same. The chamber C is provided at its upper portion with an inlet-tube t , communicating with valved branch tubes t^2 . A pressure-gage t^3 is connected with said tubes between the valves t^6 t^4 , so as to show the pressure in the chamber C. The pipes t^2 t^3 are connected with suitable sources of carbonic-acid gas and compressed air, respectively. After all the cocks are closed on the carbonating-chamber and the plug b' inserted the agitator is operated by means of a belt applied to one of the pulleys c^5 on the shaft c^6

of the agitator. Carbonic-acid gas and compressed air are allowed to enter the chamber for from thirty to sixty minutes, the time depending upon the pressure employed. The mixing operation having been completed, the contents of the chamber are permitted to flow through the tube c' into one of the settling-vats D. Here the mass is allowed to settle and filter, the solid matter, which may be termed the "precipitate" or "sludge," settling to the bottom of the tank and remaining within the filter-cloth d^8 , while the liquid passes through the cloth and through the perforations of the inner shell d^7 and accumulates in the space between the inner and outer shells and also stands supernatant upon the sludge. The valve e^2 of the pipe e' is opened and the valve e^4 of the pipe e^3 is opened and the air-pump E' started, whereby a suction is created in the pipe f' , coil F, spout g , pipes e' and e , and bore d^4 , so that the supernatant liquid is drawn up through the bore d^4 and the flexible tube e and flows down through e' g and the condensing-coil F, the whole forming a siphon, the action of the pump E' being continued, if necessary, to carry on the operation. The pipe e^3 serves for drawing off the liquid filtering out from the mass and located below the level of the float. The liquid is discharged by the coil F into the lower tank A'. The sludge is now permitted to flow through the comparatively large tube g' into the vacuum-pan G. The pan is provided with a jacket G^2 , to which steam is admitted by the valved supply-pipe h , which is connected with any suitable source of steam. The valve e^2 is closed and the pump E' set in operation, so as to reduce the pressure within the pan. By the heat and the reduction of atmospheric pressure the remaining liquid in the sludge is rapidly and thoroughly driven off. The mass is agitated by the agitator G', which facilitates the distilling operation. When reducing the pressure within the vacuum-pan, the air removed by the pump E' is drawn through the spout g , coil F, and pipe f' and delivered through pipe f^2 into the tank A', from which it is forced by the succeeding quantity of air in outward direction through the pipe o , escaping from the latter below the level of the liquid in the vessel O and bubbling up through said liquid. The vapors of aldehyde and acetic acid, together with the aqueous vapor, if any, condense in the coil F, and the liquid of condensation collects in the tank A'. The pump and agitator are stopped when the distilling operation is complete and atmospheric pressure restored in the vacuum-pan by opening either of the vent-cocks a^6 at the upper portion of the pan. Oil is then admitted to the pan through a suitable pipe a^4 and the agitator again set in motion, so as to thoroughly mix the white lead with the oil. The quantity of oil admitted depends upon the quantity of white lead in the pan G and in any case is sufficient to render the mixture fluid

enough to be drawn off through pipes i^2 into the tanks I, where it is allowed to settle and is then removed for packing or use. The liquid collecting in the tank A' is pumped by means of the pump E, through the pipes $a^2 a^5$, up to the tank A for use again in the process.

The pipe n , with its valve n' , affords communication between chamber C and the vat D, so that any desired pressure of gas can be exerted on the surface of the mass in the vat for assisting the discharge of the same through the tube g' into the pan G when the valve s of said tube is opened. Water for washing the chamber C or for any other purpose may be supplied thereto through the valved pipes n^3 . The vent-cock n^4 serves for restoring atmospheric pressure within the settling-chamber or for permitting the escape of air therein when charging the same. The spout g of the pan is provided with a check-valve h' , so as to maintain the vacuum in the pan, and the pipes $e' e^3$ are connected with said spout beyond said valve—i. e., at the opposite side to the vacuum-pan.

In Fig. 2 the filter-cloth d^8 is removed for a part of the distance from the top of the settling-vat, so as to expose the inner shell d^7 to view. A number of charges from the carbonating-chamber may be admitted to one of the settling-vats, the combined mass in said vat not being discharged into the vacuum-pan until the settling-vat is approximately full. The next charge from the carbonating-chamber and succeeding charges may then be charged into the other settling-vat. The air-pump E' serves two purposes—i. e., starting the siphon action through the pipes $e' e^3$ and for reducing atmospheric pressure within the pan G.

By the apparatus described the process of making white lead may be carried on almost continuously, the settling-vats being used alternately, and the same, in connection with the pan, condenser, and pump, providing means for rapidly and efficiently withdrawing the solvent fluid employed from the white lead.

In the carbonating-chamber the litharge (PbO) is converted by the action of the solvent fluid and the carbonic-acid gas into white lead, (lead carbonate, $PbCO_3$.) In the remaining portions of the apparatus the white lead is separated from the solvent fluid and the solvent fluid returned for use in repeating the process.

Having thus described my invention, I claim as new and desire to secure by Letters

60 Patent—

1. In an apparatus for making white lead, a settling-chamber, a float in said settling-chamber, a siphon-pipe connected with said float and extending outside the same, and a discharge-pipe communicating with the lower part of the chamber below the float, substantially as set forth.

2. In an apparatus for making white lead, a settling-chamber, a vacuum-pan, a spout connected with said vacuum-pan, a discharge-pipe from the settling-chamber to the vacuum-pan, a float in said settling-chamber, and a siphon-pipe connecting said float with the spout, substantially as set forth. 70

3. In an apparatus for making white lead, 75 a settling-chamber, a vacuum-pan, a spout connected with said vacuum-pan, a discharge-pipe from the settling-chamber to the vacuum-pan, a float in said settling-chamber, a siphon-pipe connecting said float with the spout, and a condenser connected with said spout, substantially as set forth.

4. In an apparatus for making white lead, 85 a settling-chamber, a vacuum-pan, a spout connected with said vacuum-pan, a discharge-pipe from the settling-chamber to the vacuum-pan, a float in said chamber, a pipe connecting said float with the spout, a condenser connected with said spout, and an air-pump connected with said condenser, substantially 90 as set forth.

5. In an apparatus for making white lead, a settling-chamber consisting of an outer shell, an inner perforated shell and a lining of filtering material within said inner shell, a float 95 in the settling-chamber within said lining, a siphon-pipe connected with said float and extending outside of the chamber, a discharge-pipe connected with the interior space of the settling-chamber below the float, and a discharge-pipe connected with the space between the inner and outer shells, substantially as set forth. 100

6. In an apparatus for making white lead, 105 the combination, with a settling-chamber having an outer shell, an inner perforated shell and a lining of filtering material within the inner shell, of a float in said settling-chamber within said lining, a vacuum-pan, a discharge-pipe connecting the interior space of 110 the settling-chamber with the vacuum-pan, a spout connected with the vacuum-pan, a siphon-pipe connected with the float and with said spout, and a discharge-pipe connecting the space between the inner and outer shells 115 with said spout, substantially as set forth.

7. In an apparatus for making white lead, a plurality of settling-chambers provided each with an outer shell, an interior perforated shell and a lining of filtering material within the inner shell, floats, one in each settling-chamber, a vacuum-pan, discharge-pipes, each connecting the interior space of one settling-chamber with the vacuum-pan, a spout connected with said vacuum-pan, siphon-pipes, one for each float, connecting the same with said spout, a discharge-pipe connecting the space between the inner and outer shells with said spout, a condenser connected with said spout, and an air-pump connected with 125 said condenser, substantially as set forth. 130

8. In an apparatus for making white lead, a plurality of settling-chambers provided each with an outer shell, an inner perforated shell

and a lining of filtering material within said inner shell, floats, one in each settling-chamber, a vacuum-pan, valved discharge-pipes, one for each settling-chamber, connecting the interior space of the same below the float with the vacuum-pan, a spout connected with said vacuum-pan, a valve in said spout, siphon-pipes, one for each float, connecting the same with the spout beyond the valve, a discharge-pipe connecting the space between the inner and outer shells with the spout, beyond the

valve, a condensing-coil connected with said spout beyond the valve, and an air-pump connected with said condensing-coil, substantially as set forth.

15

In witness whereof I have hereunto set my hand to this specification in the presence of two witnesses.
